UNITED STATES PATENT OFFICE.

WALTER T. ABEL, OF WATERBURY, CONNECTICUT, ASSIGNOR TO THE PATENT BUTTON COMPANY, OF WATERBURY, CONNECTICUT, A CORPORATION OF CONNECTICUT.

STICK PIN AND METHOD OF MAKING THE SAME.

Application filed November 13, 1924. Serial No. 749,671.

My invention relates to new and useful improvements in stickpins and to the method of making the same, and has for an object to produce an ornamental stickpin, the head of which is stamped from a blank of relatively soft metal, such as aluminum.

I have found that by forming the head of aluminum the same will flow easily when swedged and tightly grasp the pin or prong, as will be hereinafter more fully described.

Furthermore, the head when formed of this metal presents a polished or silvery appearance, will not tarnish, and is soft enough to take a clean and clear cut ornamental impression from the die.

Another object of the invention is to provide the rear of the head with a hub in which there is a slot extending nearly across the same and into which will be fed the pin or prong, after which the head will be subjected to a punch which will swedge the metal about the slot inwardly and downwardly to thereby tightly anchor the pin or prong within the head.

The invention in its broadest aspects is somewhat similar to the invention shown in the application filed by me in the United States Patent Office on October 23, 1924, bearing Serial No. 745,329. In that disclosure, however, a button head is shown formed from a blank of soft metal, the blank being cut from a rod of wire, and the hub shown is a hollow one. In the present instance, however, the metal head is provided with a hub in which there is formed a slot for the reception of the pin or prong.

Another object of the present invention is to form a stickpin, the head of which is formed from a soft metal blank and one of the dies to which this blank is subjected is engraved or stamped with some ornamental configuration; also, the hub thereof is slotted for the reception of the pin or prong. These heads are then subjected to a second set of dies and before the plunger descends the pin or prong is fed to the slot in the hub and the hub then swedged to form the complete article.

Still another object of the invention is to provide a stickpin, the head of which, and even the prong are made of relatively soft metal, the pin swedged tightly within the head and the entire operations being performed at a maximum rate of speed.

With these and other objects in view, the

invention consists in certain new and novel constructions and combination of parts as will be hereinafter more fully described and pointed out in the claim.

Referring now to the drawings showing a preferred embodiment of the invention,

Fig. 1 is a view partly in elevation and partly in section, showing the pin head and prong being subjected to the swedging operation.

Fig. 2 is a view of the punch for swedging the head and anchoring the pin or prong in position, taken at right angles to Fig. 1.

Fig. 3 is a bottom plan view of the punch.

Fig. 4 is a top plan view of the die.

Fig. 5 is a sectional view thereof.

Fig. 6 is a bottom plan of the pinhead showing the slot for the reception of the pin or prong.

Fig. 7 is a side elevation of the same.

Fig. 8 is a detailed view of the blank from which the head is made.

Fig. 9 is a rear view of the completed pin, and

Fig. 10 is a side elevation of the completed pin, the prong being shown in section.

At the outset it might be stated that the design as shown for the head of this pin is the subject of an application for a design patent filed by Leonard R. Carley, October 22, 1924, bearing Serial No. D 11,139, but it is to be understood that the head of the stickpin may have any design formed thereon, as desired.

Referring now to the several figures, there is shown in Fig. 1 a die 1 having cut in its upper face 2 a design of a dog's head, as shown by the numeral 3. A plunger or punch 4 is shown having cut therein the sloping side wall 5 and the short transverse passage 6 through which the pin or prong 7 may pass.

Referring now specifically to the pinhead there is shown in Fig. 8 a blank of soft metal which is subjected to a set of dies (not shown) to press the blank into the pinhead 8, as shown in Fig. 7, the pin head being provided with the hub 9, the side walls of which are vertical, while within the hub is pressed the slot 10.

The first dies for forming this head (not shown) will have an ornamental configuration cut in one of their faces to stamp the desired design on the face of the button head, and the head in the form shown in Fig. 7 will then be subjected to the punch and die as shown in Fig. 1. At the same time, the prong 7 which is formed of a wire will be cut and

shaped and fed to the slot 10, after which the plunger 4 will descend to swedge the metal about the slot 10 around the one end of the prong and thus anchor the same rigidly in position. By comparing Fig. 7 with Fig. 10 it will be seen that the entire character or shape of the hub has been changed, as the swedging action due to the sloping walls cut in the plunger 4, force the side walls of the hub inwardly and downwardly to completely fill up the slot and tightly anchor the prong in position. It will be understood that the configuration cut in the die 1 will be the same as cut in the first die (not shown) which forms the pin head from the blank, as shown in Fig. 7.

The making of the pin in its entirety starting with the blank, and then with the shaped pin head also, the prong being cut and then fed to the plunger and die shown in Fig. 1, is all performed in one automatic header and these pins may be turned out at the rate of between one hundred and one hundred fifty a minute.

I am aware that it is old to clamp a prong or wire by bending over metal arms, but in the present instance, it will be seen that I have formed a pin head having a hub and slot into which is passed a pin or prong and the entire hub being swedged has changed its character

to tightly anchor the pin in position. In the finished article, it will appear as if the prong had been inserted in a hole in the hub and soldered, rather than simply having the metal of the hub swedged about the same.

The metal is relatively cheap, takes a clear cut impression and also flows easily, making the entire cost a very low one and at the same time forming a very pretty stick pin.

Many slight changes might be made without departing from the spirit and scope of the invention.

Having thus described my invention, what I claim as new and desire to secure by Letters Patent is:

A pin comprising a head member of soft metal having a cylindrical hub at the side thereof, provided with a slot at the outer end, said slot being disposed diametrically of the hub and leading in from one side thereof and terminating short of the diametrically opposite side thereof and a pin having an end inserted in the slot, the material of the hub over that portion of the pin which is located in the slot being compressed upon the pin to fix the same upon the hub.

In testimony whereof I affix my signature.

WALTER T. ABEL.
